TRANSFORMER CONSTRUCTION

Leo L. Verkuil, Norwalk, Conn., assignor to Edwards Company, Inc., Norwalk, Conn., a corporation of New York

Application February 24, 1951, Serial No. 212,609

27 Claims. (Cl. 317—15)

1

This invention relates to the construction and mounting of electrical transformers and to casings therefor. This application is a continuation-in-part of my application Serial Number 71,607, filed January 19, 1949, now abandoned.

More particularly, it relates to that type of transformer which is adapted to be secured to an outlet box or to be secured to a bracket or cleat on a wall. Generally speaking, the type of transformer for which the present invention is particularly useful is the type used to reduce the voltage of, illustratively, the ordinary house lighting supply circuit (115 or 230 volts) to a lower voltage, say, 6 volts or 24 volts, for use in a bell-ringing or other signalling system or other low voltage utility.

Prior art transformers of the type with which the present invention is generally concerned are subject to a number of serious defects. Such prior art transformers have been designed with pedestals attached thereto for mounting on a wall bracket or cleat, and expedients have been attempted so that, without use of the pedestals, the transformer may be attached to a standard outlet box and secured thereto. However, when attached in this manner it has been possible that some portion of the transformer is closer to the wall or other structure on which the outlet box is mounted than is consistent with safety, having in consideration the hazard from fire. For example, Underwriters Laboratories, Inc., the recognized authority on the construction and installation of devices which under some circumstances may become fire hazards, has specified a minimum distance from any part of a transformer so mounted to the nearest wall. That authority prescribes the standard minimum distance for transformers of the above-described type as one-quarter of an inch.

An object of the present invention is to provide a transformer construction which has a mounting pedestal integral with the casing of the transformer and which is capable of being readily interrelated with a standard outlet box, but cannot be mounted or secured to it in any position without maintaining a minimum predetermined clearance between the transformer itself and the wall upon which the outlet box is mounted.

Another object is to provide a transformer construction in which the means for mounting it on an outlet box are of simple and readily fabricated construction and simple and convenient to manipulate, and, desirably, have no parts such as bolts or nuts which must be removed

2

when mounting it, yet assures that the transformer is tightly and positively secured to the outlet box.

Another object is to provide such a transformer construction which is easy and economical to construct and to install and which has inherent safety in use. Another object is to provide a transformer construction in which the heavy lead wires, such as those that are to be connected inside the outlet box, are strongly and dependably anchored and well adapted to resist pulling thereof or strains thereon. Another object is to provide a transformer of the just-mentioned type embodying, in a compact manner and capable of ease of assembly, a temperature-responsive cut-out which may also be adapted to serve as a lead-in anchorage and which may be constructed in a manner readily to compensate for possible strain imposed thereon during assembly.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which is shown an illustrative embodiment of this invention and in which similar reference characters refer to similar parts throughout,

Figure 1 is a perspective view of the transformer structure and of an outlet box, showing the former in a position ready to be secured to the outlet box;

Figure 2 is a plan view as seen along the line 2—2 of Figure 1, with the outlet box shown in horizontal section, showing the transformer structure assembled to the outlet box, all in relation to the wall or other supporting surface to which the outlet box is secured;

Figure 3 is an end elevation of the transformer structure as it would be seen from the left in Figure 2 prior to its assemblage to the outlet box;

Figure 4 is a plan view of the transformer structure as seen with a portion of its casing structure removed;

Figures 5 and 6 are transverse sectional views as seen along the line A—A of Figure 4, showing by way of illustration two forms of spreader arrangements for certain of the transformer casing parts;

Figures 7 and 8 are plan views respectively of a sheet-metal conductor clamping plate and

of a coacting insulating plate which are assembled and related to the core and winding as shown in Figure 4;

Figure 9 is a detached side elevation, as seen from the left of Figure 4, of a temperature-responsive switch structure, and

Figure 10 is a vertical sectional view as seen on the line 8—8 of Figure 9.

The transformer comprises a core C, illustratively laminated and of any usual form, generally rectangular in outline as shown in Figures 1, 2, and 3, and a casing A—B which has bulges in its sides to accommodate the interior windings associated with the core C. Illustratively, the windings, as in known constructions, can extend about a middle leg of the core and through core windows, as indicated in Figure 5, where the windings are indicated by the reference character W.

The transformer casing A—B is preferably made of sheet metal, thus to facilitate stamping operations to produce and shape it, and in the illustrative embodiment it comprises two half-housings generally indicated by the respective reference characters A and B. Each half-housing is stamped or shaped to the respective conformations hereinafter described and they can rest, as shown in Figures 1 to 3, against the respective side faces of the core C; half-housings A and B and the laminations forming the transformer core C are clamped together by any suitable means, such as bolts 10 and nuts 11, which enable the casing to be taken apart if desired. Rivets or clamps may be used instead of bolts and nuts for this purpose.

Half-housing A, as is better seen in Figures 2 and 3, has a bulging or dished-out central portion 12 of substantially rectangular configuration, with rounded edges and corners, and as seen in Figures 2 and 3, the central portion 12 extends upwards from a flat marginal or base portion 13 which rests against one side face of the core C. As shown in Figures 1 to 3, the bolts 10 pass through this marginal or base portion 13 of half-housing A. In Figure 2 is indicated a dimension *a* which indicates the maximum depth of the bulging or dished-out portion 12, being the distance from the inside face of the base portion 13 to the outside surface of the dished-out portion 12, which surface (Figures 2 and 3) is flat.

Half-housing A has an extension 17, to the left in Figures 1 and 2 and toward the observer in Figure 3, which is formed integrally with and as part of half-housing A, is slightly tapered as shown, and it ends in a substantially semi-circular ring-like flange 18; as shown in Figure 2, it overhangs one end face of the core C; its lower overhanging edges (Figures 2 and 3) are substantially in the plane of the inside face of the base portion 13, which plane is coincident with the plane of the core face against which the half-housing A rests. Also, as appears in Figure 3, the extension 17 overhangs an end of the core C substantially at its midpoint. The center or axis of the semi-circular ring-like flange 18, while falling substantially in a vertical plane through the center of the core C as viewed in Figure 3, is displaced or offset vertically from the horizontal plane through the center of core C.

The right-hand portion of the tapering extension 17 as seen in Figure 2 overlies the upper face of the left-hand leg of the core C, providing ample passageway for the input leads 16—16, usually heavily insulated as shown, and they can

thus overlie that transformer leg, as is shown also in Figure 5; these leads, in the illustrative embodiment, are the ones that are to be connected to the building lighting circuit, usually of about 110 volts, and they are connected in any suitable manner to the high voltage coil of the windings W, illustratively as indicated in Figure 5.

Just behind the half-ring flange 18 as viewed in Figure 3 and to the right as viewed in Figures 1 and 2, the extension 17 has a semi-circular depressed portion 17a (Figure 2) which is of lesser radius than the portions of the extension 17 to either side of it.

Half-housing B has a dished-out portion 19, in general similar to the dished-out portion 12 of half-housing A, having a base or marginal portion 23 that rests against a side face of the core C where it is held by the bolts 10. In the dished-out portion 19 is a generally centrally located opening adapted to securely hold a flat piece of insulating material which serves as a terminal panel 20 provided with binding posts or screws 22, illustratively two in number, to which output leads 21 may be attached; the binding posts 22 are connected internally of the transformer structure and in any suitable manner to the low voltage coil of the windings W, that coil supplying lower voltage, illustratively 6 volts or 24 volts.

In Figure 2, on the half-housing B, is indicated a dimension *b*, which represents the depth of the dished-out portion 19, that is, the distance from the inside face of base or marginal portion 13 to the outside face of the flat wall of the dished-out portion 12.

At the left-hand end of half-housing B as viewed in Figures 1 and 2 and at the forward end as viewed in Figure 3, half-housing B has a tapered extension 26 formed integrally with and as part thereof; similarly to extension 17 of half-housing A, extension 26 terminates in a semi-circular ring-like flange 27 and adjacent the latter it has a depressed portion 26a of lesser radius than those parts of the extension that are to either side of it. The lengths of extensions 17 and 26 are the same so that they project beyond an end face (the left-hand face in Figure 2) of the core C by the same distance.

Unlike extension 17 of half-housing A, which is attached to the latter throughout its semi-circumference, extension 26 of half-housing B is cut away from half-housing B except for a small portion of its semi-circumference, and because of the above-described offset of extension 17 of half-housing A (see Figures 2 and 3), this relatively small uncut portion is left, as indicated at 30 in Figures 2 and 3, along the line of the outer edge of the base or marginal portion 23 of the half-housing B, so that the semi-circular tapered extension 26 can occupy a position where it is complementary to the extension 17, namely, in the angle (see Figure 2) between the end face of the core C and the overhanging extension 17 of half-housing A. When the parts are thus assembled, semi-circular or half-ring flanges 18 and 27 form a complete circular opening (see Figure 3); together, the extensions 17 and 26 form a tubular projection from the bulk of the assembled structure, of substantially circular cross-section, and because of the above-described taper in each extension, this tubular projection decreases in diameter as its length increases and it terminates in a subdivided annular flange made up of the semi-circular flanges 18 and 27 with the intervening short section of reduced radius

which is made up of the two above-described depressed semi-circular portions 17^a and 26^a which together, in effect, form an annular groove. Moreover, the center line or axis of this tubular projection or tube-like extension 17-26 is offset (see Figure 3) from the horizontal midplane of the transformer structure (see also Figure 2).

Moreover, the complementary extensions 17 and 26 form a substantially circular channel through which the input leads 16-16 may pass from the inside of the casing to the exterior thereof. In the circular opening formed by the flanges 18 and 27 is placed an insulating disc 29 with holes to accommodate the input leads 16; as shown in Figure 2, the semi-circular flanges 18 and 27 are externally convex, forming a smooth rounded-over exterior and, being externally convex, the flanges 18 and 27 are thereby internally recessed throughout their respective arcuate extents, each about 180 degrees as shown in Figure 3, and insulating disc 29, as is better shown in Figures 2 and 3, is seated in these complementary arcuate recesses which thus coat to hold the insulating disc 29 transversely of the axis of the tapered tubular extension formed by the complementary extensions 17 and 26. Also, as shown in Figure 3, the holes in disc 29 are spaced apart by a substantial distance and they thus, also, insulatingly hold the input leads 16-16 correspondingly spaced apart.

The small uncut portion 30 (Figure 3), through which the extension 26 remains joined to the half-housing B, acts like a hinge and allows the half-ring flange 27 to be displaced substantially radially (in a direction in line with its vertical radius as seen in Figure 3), relative to its complementary half-ring flange 18 on the complementary extension 17. The complementary extensions 17 and 26 may thus be spread apart and the tubular extension 17-26, in effect, expanded at its outermost end, and in the specific illustrative embodiment above described, the connecting portion 30 between extension 26 and half-housing B being flexible, the expansion takes place in the direction of the vertical diameter as seen in Figure 3.

Suitable spreader means are provided, preferably in the form of a screw or bolt 31 that passes through a threaded hole 26^b in extension 26 and which is anchored at a point in extension 17 that is opposite the threaded hole in the extension 26, whereby upon turning of the screw or bolt, as by a screw-driver where it has a slotted head as shown, the extensions are spread apart, the tubular extension 17-26 being deformed, at its outer end, by enlargement along the vertical diameter as viewed in Figure 3. Interiorly of the tube-like extension 17-26, the bolt or screw 31 is sheathed in a sleeve 32 of insulating material as shown in Figure 2 (see also Figures 4, 5, and 6), in order, as appears from Figure 3, to insulatingly by-pass the insulated input leads 16-16 and between which the bolt 31 extends, the spaced holes in the insulating disc 29 coacting to hold the insulated conductors 16-16 spread apart so that, within the tubular extensions 17-26, each can pass to one side of the bolt 31.

For purposes of assembly in course of manufacture, there are many advantages in offsetting the tubular extension 17-26 so that its horizontal median plane as viewed in Figures 2 and 3 coincides with the plane of the upper face of the core C; as seen in Figure 4, assembly and connection of the heavy high-voltage leads 16-16

are greatly facilitated. However, a disadvantage lies in the fact that a direct pull, to the right in Figure 4, on the external ends of leads 16-16 might impose an undesired and detrimental strain on the internal electrical connections with the usually very thin wires of the high-voltage winding, with the risk of rupturing them. Accordingly I make provision for overcoming such risk so that pulling on the leads 16-16 to make the connection to the parts within the outlet box D can be safely effected, and this I carry out in a manner to achieve anchorage even though the transformer structure has embodied in it a temperature-responsive safety cut-out as it at times desirable or prescribed.

In Figures 4 and 9, I have shown a preferred form of temperature-responsive cut-out. It comprises a heavy fiber plate-like support 41 having a downward extension 42 that extends into the left-hand core window 43 of the core C. The latter is of the shell type, having a middle core leg 44 which passes snugly through the windings W and the heavy fiber winding end plates 45-46 that are substantially octagonal, shaped so their right-hand vertical edge faces, as seen in Figure 4, abut against the inside face of the right-hand core leg and their left-hand vertical edge faces are spaced from the inside face of the left core leg by a distance equal to the thickness of the fiber support 41; the latter rests against the left-hand vertical ends of winding plates 45-46 with its downward extension 42 snugly fitted into the space between the left core leg and these vertical plate ends. The fiber support 41 is thus mounted and held to resist forces transversely of its plane, particularly forces to the right in Figure 4. Its ends overlie the core C and its upper edge (Figure 9) may be conformed to the shape of the inside face of the bulging part of half-housing A so that when the latter is assembled to the core C and its counterpart half-housing B, as by the bolts 40-40, fiber support 41 is securely clamped between housing part A and the core C.

Fiber support 41 carries a thermally-responsive switch structure which comprises two elongated flat metal parts 47 and 48, each on one side of support 41, to which they are clamped at one end by a hollow rivet or eyelet 50 so as to extend toward the other end where they overlie an aperture 51 (Figures 9 and 10). A combination washer and bushing 47^b of insulating material insulates part 47 from the eyelet 50 and part 48. One of the parts, 47, has an area or portion 47^a, illustratively circular, that is stamped or pressed out of its plane so as to project into the aperture 51, acting as a guide to resist any tendency of part 47 to swing, about the rivet 50, out of juxtaposition to the other switch part 48. The latter is prevented from swinging about the rivet 50 by an extension 48^a that is bent into a cut-out 41^a in support 41. The free ends of parts 47-48 are thus maintained opposite each other, at the aperture 51, where each, as shown in Figure 10, has a contact point of suitable alloy for engagement with each other to close an electrical circuit. Intermediate its ends, support 41 has a large aperture 52 which extends above and below the plane of the upper face of core C as viewed in Figures 3 and 4 and thereby substantial lengths of the switch parts 47-48 are insured of exposure to the temperature created inside the housing A-B by the operation of the windings W and by heat losses in the core C.

One of the switch parts, such as part 48, is

bimetallic so that, being clamped by eyelet 50 at one end, it bows, upon increase in temperature, in a direction to move its other end away from the plane of support 41 and hence away from and out of contact with the end of companion switch part 47 exposed in aperture 51, thus breaking the circuit at the contact points. When connected in circuit with the high-voltage coil of windings W, the circuit can thus be broken upon temperature rise due to overloading. Switch part 47 is provided with a tab 47^c to which the thin lead wire from one end of the high-voltage winding is secured, as by wrapping and soldering, after passing it through a hole in end plate 45 of the windings W. One of the heavy lead-in conductors 16, after stripping its end of insulation, is projected through the eyelet 50, then bent over, and soldered to the eyelet. Full or stress exerted on that lead-in conductor 16 is resisted by the rigidly clamped fiber support 41 and is not exerted on the thin lead from the coil; were plate 47 to yield, it would yield to the right in Figure 4 and could not tension the thin lead-in from the coil. However, provision is also made to relieve the fiber support 41 from substantial stresses in that the lead-in connected thereto may be held in a manner about to be described.

Resting upon the upper face of middle leg 44 (Figures 4 and 3) is a suitably heavy sheet-metal plate 54 (Figure 7) provided with end tongues 55-56 and overlying it is an I-shaped plate 57 (Figure 8) of insulating material, of the same width but longer, being cut out at 57^a and 57^b; both are tightly held and anchored between the leg 44 and windings W, being put in place upon assembly of pre-formed windings W to the middle leg 44 with the fiber sheet 57 toward the inside of windings W. Tongues 55-56 are bent upwardly into the cut-outs 57^a and 57^b of the insulating plate 57, preventing relative displacement between the two.

Where the transformer includes a cut-out 47-48 as above described, and to which one of the heavy input-leads 16 is anchored, that lead is passed over the insulating plate 57 and between the tongue or lug 55 and winding end plate 45, as shown in Figure 4, whence the tongue 55 is bent over it to clamp it tightly against the anchored metal plate insert 54, with the fiber plate 57 interposed. Thus the fiber support is protected against the effect of substantial stress that might be imposed on the lead-in. The other input-lead 16, or, in case the structure does not include the cut-out switch 47-48, both input-leads 16-16 are secured in the manner now described with respect to the lower lead 16 as seen in Figure 4; the heavy lead is first bent back upon itself to form a hook H, the short end of which is inserted between the then-upstanding tongue 56 and winding end plate 45, whence the tongue 56 is bent over it and forced home toward the metal insert plate 54 to clamp the short end between tongue 56 and the metal plate 54 with the insulating plate 57 interposed therebetween. The resultant anchorage is strong and does not slip, for the heavy lead is hooked around the tongue and the tongue clamps and holds the short end of the hook against unbending and without unbending no slipping takes place. No stress is transmitted to the thin high-voltage coil lead wire which, after passing through a hole in end plate 46, is soldered to the bared wire of short end of the hook H.

When the fiber support 41 is clamped between the core C and half-housing A, strains are fre-

quently set up in the part 41 and it is sometimes distorted so that an initial setting of its bimetallic part for functioning to open the circuit at the desired temperature is disturbed. This is in part counteracted by the provision of the apertures 51-52 which remove a major part of the fiber support 41 from inbetween the switch arms 47-48, giving their major portions a sort of free-floating effect. Upon final test-checking, however, when assembly is completed, any departure in setting is corrected by an arrangement that does not require taking the half-housings apart. In switch part 48 is threaded a screw 58 whose free end abuts the fiber support 41 (Figures 4 and 9), and in half-housing A I provide a small round hole 59 (Figures 2 and 1) which is coaxial with the axis of the screw 58. A small screw-driver inserted through the hole 59 serves to turn screw 58, which is close to the eyelet support 50, to strain the switch part 48 in a direction toward or away from its companion switch part 47, as the case may be, to effect circuit-opening at the desired temperature. The structure is then ready for installation.

The above-described floating form of support for the coating ends of the parallel switch elements 47-48, furthermore, serves to tend to preserve the temperature setting should the lead-in wire 16 anchored to the composition fiber or plastic support 41 strain the latter; any stress causing such strain is imposed on support 41 at the eyelet 50 by which elements 47-48 are secured, and such strain does not disturb either element relative to the other and, at the most, shifts the two as a unit, and this action is aided in that the intervening portions of support plate 41 are cut away so as not to impede such shifting.

The inner end of the spreader bolt 31 bears against the rigid extension 17 at a point opposite the threaded hole 26^b in the movable extension 26 and is suitably anchored in the extension 17. In one form the bolt 31, at the end opposite its head, is anchored in extension 17 part-way along its length so that turning the bolt 31 spreads extension 26 away from extension 17 or draws it toward extension 17, depending on which way the bolt is turned. An illustrative arrangement of this kind is shown in Figure 6, where an intermediate portion of the bolt passes through a hole, which thus forms a seat or socket, in a depression in the wall of extension 17, its end is externally headed over, and such arrangement anchors the free end of the bolt against sidewise displacement under the stress of spreading one extension away from the other. Or the bolt may be anchored against such sidewise displacement, by simply having its inner end portion seated in an internal recess or seat in the wall of extension 17 at a point opposite the threaded hole 26^b in the extension 26, as indicated in Figure 5, where the internal seat or socket is formed in a depressed portion of the sheet metal of the extension 17.

Standard outlet boxes, such as is shown at D (Figures 1 and 2), consist of a back wall 33, four side walls 34, 35, 36, and 37, and a cover plate (not shown). The walls are provided with knock-outs seated in the several openings 38 that are usually provided in each wall (only one is shown in the back wall in the interest of simplicity); these are of the usual type and, as is known, any one or more knock-outs may be removed to expose and make available the desired hole or holes through which the wiring

of the building circuit or circuits is usually brought into the outlet box for electrical interconnection. In standard outlet boxes the distances from each of the openings or holes 38 in the side walls 34, 35, 36, and 37 to the back of the back wall 33 is fixed and invariable, and when the box is secured with its back wall 33 against a wall surface or wall 39, as by screws 40 (Figure 2), these openings 38 in the side walls are all spaced from the face of the wall 39 by the same invariable distance which, from the center of the hole 38 to the face of the wall 39, is indicated in Figure 2 by the dimension *c*. Safety rules against fire hazards require that in mounting a transformer in relation to a surface-mounted outlet or panel box for connection of its high voltage terminals to circuit conductors within the box, the transformer must not be given a position relative to the wall 39, which is not infrequently a wood panel, less than a prescribed minimum, for example, one-quarter of an inch. In Figure 2 a dimension *d* indicates a spacing of the transformer from the wall 39 by a distance not less than the required minimum for safety. Illustratively, the distance *c*, being the spacing of the centers of the side wall holes 38 from the face of wall 39, may be seven-eighths of an inch. According to certain features of this invention, it is possible to make certain that the transformer cannot be assembled to the outlet or panel box without meeting at least the minimum safety requirement of spacing of the transformer from the wall 39.

As above noted, the depressed half-circular portions 17^a and 26^a of the extensions 17 and 26 together form an external annular groove or neck, and as appears from Figures 1 and 2, the radius of this annular groove is commensurate with the radius of a hole 38 in the outlet box, one of which holes (the center one in the wall 35 of Figure 1) is shown with its knock-out removed and hence with its ring-shaped wall exposed, the width of the latter being about the same as the thickness of the metal of the side wall 35.

The longitudinal axis of the tube-like extension 17-26 lies substantially in the plane of the upper face of the core C, as viewed in Figures 2 and 3, and against which face the half-housing A rests; as appears clearly in Figures 2 and 3, all parts of the transformer structure that extend upwardly from or beyond this upper face of core C and hence extend upwardly from the longitudinal axis of the tubular extension 17-26, fall within the dimension *a* (Figure 2) which, where dimension *c* is illustratively seven-eighths of an inch and the minimum value of the spacing dimension *d* is one-quarter of an inch, is five-eighths of an inch. But, as seen in Figure 3, all parts that extend to the right or to the left of the vertical plane through this longitudinal axis of the tubular extension 17-26, extend beyond that axis materially more than the sum of the dimensions *a* and *d*. Also, all parts that extend below, in Figures 2 and 3, the horizontal plane through this longitudinal axis of the tubular extension, have an extent greater than the sum of the dimensions *a* and *d*. Though, because of symmetry of internal construction in the illustrative embodiment, dimensions *a* and *b* in Figure 2, being the respective depths of the dished-out portions 12 and 19 of the half-housings A and B, respectively, are equal, the offsetting of the half-circular extension 17 upwardly toward the horizontal plane of the flat

face of the dished-out portion 12 and the offsetting upwardly and in the same direction (Figures 3 and 2) of the half-circular extension 26 from the flat face of the dished-out portion 19 are such that, in the illustration, the dimension *a* (Figure 2) is less than the dimension *c* by at least the dimension *d*, and the dimension *f* (Figure 2) exceeds dimension *c*.

Accordingly, and as seen in Figure 3, the longitudinal axis of the tube-like extension 17-26 is spaced from the two parallel sides of the structure (being, in effect, the left and right-hand side faces of the core C in Figure 3), by a distance greater than the dimension *c*, and is spaced from the plane of the bottom face of the dished-out portion 19 of the housing part B also by a distance greater than the dimension *c*, but is spaced from the opposite or upper parallel face of the dished-out portion 12 of the housing part A by a distance that is less than the dimension *c* by an amount at least equal to the safety dimension *d*. That means that the transformer structure can have its tube-like extension 17-26 entered into the open hole 38 in the side wall 35 of the outlet box D only when the half-housing part A with its half-circular extension 17 is brought to face the wall 39.

The input leads 16-16 are first entered through the open hole 38 and thereupon the sub-divided tube-like extension 17-26 is entered into the open hole 38 through which the half-circular rounded-over flanges 18 and 27 just about pass, with the extension 26 not spread away from extension 17, which is the position of the parts as shown in Figure 3; and in which position the flanges 18 and 27 form a complete circle, as above noted. As indicated in Figure 2, the tapered walls of the extension 17-26 are such that they limit the entry of the tubular extension 17-26 into the hole 38 to a point where the annular groove formed by the depressed portions 17^a and 26^a are in juxtaposition to the ring-like wall of the hole 38, whereupon the bolt 31 is turned to spread extensions 17 and 26 so that the depressed or grooved portions 17^a and 26^a are forced radially apart and against the edge-like wall of the hole 38, the spreading action thus achieved expanding the rounded-over flanges 18 and 27, to the left or on the inside of the outlet box wall 35 (Figure 2), to a dimension greater than the fixed dimension of the hole 38. The transformer structure is thus firmly secured to the wall 35 of the box and is firmly held in place. Thereafter the necessary wire connections are made to the input leads 16-16. It is to be noted that the transformer structure may thus be mounted in position quickly and with a minimum of manual operations and that what operations are performed to secure it in place are carried on outside of the box D, excepting for making the wire connections. Moreover, at least the minimum required spacing of the structure from the wall 39 is practically automatically achieved.

As appears from Figures 1 and 2, the head of the screw 31 is exposed at that face or side of the transformer structure that is opposite that face which, for safety reasons, it is desired to have spaced from though facing toward the wall 39, and thus the only position from which the screw head is most conveniently accessible for spreading the sub-divided gripping parts is the one which gives the desired spacing of the structure from the wall.

The amount of spreading, at the outer end portions of the tube-like extension 17-26, to

tightly secure the structure against the walls of the hole 38, need not be very great, as appears upon comparing Figure 3 (unspread) with Figure 2 (where the parts are spread apart), and the spreading action, which takes place by a slight counter-clockwise pivoting of the extension 26 about the hinge-like bending of the portion 30, is accompanied by a tilting of the plane of the half-circular flange 27 out of alignment with the plane of the companion half-circular flange 18, as shown in Figure 2; the insulating disc 29 thus remains dependably held within the companion half-circular recesses in the flanges 18 and 27, being in effect gripped by the side walls of these arcuate recesses because of the just-mentioned relative tilting that takes place, all as shown in Figure 2.

The transformer structure, however, is adaptable for alternative methods of mounting independently of the outlet box and also within known safety regulations, and accordingly half-housing A is provided with a downward extension (Figure 1) below the core C, being integral with the base or marginal portion 13 and at its lower end being bent outwardly at approximately a right angle to form a flange or pedestal 14 provided with holes or slots 15 to accommodate screws, bolts, or other fastening devices. Companion to the pedestal 14 is a similar and juxtaposed downward extension (Figure 1) of half-housing B, from the base or marginal portion 23 thereof, being bent outwardly at right angles to form a pedestal 24 with holes or slots 25. Pedestals 14 and 24 are in the same plane, and as better appears in Figures 2 and 3, they extend from the base parts 13 and 23, respectively, by a distance approximately the same as the depth of the dished-out portion 12 and dished-out portion 19, respectively, of the housing parts A and B. By means of these pedestals the transformer structure may be secured to any suitable support.

These pedestals do not interfere with the desired mounting of the transformer structure to an outlet box as above described, and they can simply be disregarded when such mounting is effected. Desirably, and as above indicated, where the transformer structure has a face toward the wall 39 that is flat and of substantial area, as is the case with the flat portion of the dished-out portion 12 of the housing part A, such face is parallel to the wall face 39 so that the spacing distance d is uniform throughout, and thus a safety spacing from the wall face 39 at all internal parts of the transformer that generate heat is brought about. As is known, it is the windings and the core C which can become unduly heated, as from overloading or a defect in a circuit somewhere.

I may, however, make provision to guard against installing the transformer initially with its back face out of parallelism with the wall 39, or to guard against possible shift of the structure out of such parallelism. Thus I may provide the transformer structure with suitable relatively small and spaced elements that are engageable with the face of the wall 39; these may comprise lateral tongue-like extensions 14^a and 14^b near the respective ends of the right-angled angle 14, and as shown in Figure 2 they extend beyond the dimension a by a distance which need not be greater than the minimum safety dimension d . Spaced upwardly from the plane of these extensions 14^a and 14^b are two extensions 13^a and 13^b that are integrally formed with a right-angled extension 13^c (see Figure 1) of the upper portion

of the base or marginal portion 23 of the half-housing B and which overlies the upper face of the core C; extensions 13^a and 13^b project beyond the rear face of the core C by a distance equal to the sum of dimension a and safety dimension d .

The outer edges of all four extensions 14^a, 14^b, 13^a, and 13^b fall in a plane which is parallel to the axis of the extension 17-26, being spaced therefrom by the distance c ; this plane substantially coincides with the face of the wall 39 when the transformer structure is secured to the outlet box D and the extensions engage the face of wall 39 at sufficiently spaced points to insure that no such tilting of the transformer structure about the longitudinal axis of the tubular extension 17-26 can take place as will make the spacing of any heat-generating part of the structure less than the desired safety distance. These extension members can be brought safely into contact with the wall 39, for the purposes just described, because they are not directly subjected to any heat that might be generated internally of the transformer, and being preferably made integral with the sheet metal of the transformer casing or housing and extending away from the latter, they are relatively thin and in effect act to radiate or dissipate to the atmosphere any heat that might reach them by conduction.

These four tongue-like extensions are scored along the lines indicated at S, whereby they can be broken off if they are not needed in particular installations.

It will thus be seen that there has been provided in this invention a transformer construction and mounting therefor in which the various objects of this invention, together with many thoroughly practical advantages, are successfully achieved. Economy and ease of manufacture of the transformer housing and of its assemblage to the core structure are achieved; for example, the casing or housing may be made up in the form of the two half-housings A and B, utilizing two pieces of metal stock, such as steel or any other suitable metal, and each of these is subjected to a simple series of appropriate stamping operations and assemblage thereof to the other parts as above described effected to complete the transformer structure. In installing it, the operations are simple and speedy and can be carried on with complete safety, having the additional advantage, also, that installation can be effected without having to contend with loose parts.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In construction of the character described, in combination, an outlet box having a back wall to rest against a supporting surface and side walls and having a round aperture in a side wall thereof spaced from the center of the aperture to the plane of the back wall of the outlet box by a distance x , a transformer structure having a core and coacting windings and an enclosing casing therefor presenting four side faces, said casing having a tubular extension the axis of which is parallel to said four side faces of the transformer structure and is displaced from three of said side faces by a distance greater than x and from the fourth side face by a distance less than x by an amount providing a factor of safety against fire hazard whereby the axis of said tubular extension

and the axis of said round hole in the outlet box can be brought into coincidence only when said fourth side face is toward the plane of said supporting surface, said tubular extension having an end portion that is of a diameter commensurate with the diameter of said round aperture and is received in the latter when said fourth side face of the transformer structure faces toward the plane of said supporting surface, and means for securing said tubular extension to said outlet box side wall with the tubular extension received in said round aperture and with said two axes substantially coincident.

2. A construction as claimed in claim 1, in which said tubular extension is made of yieldable material and is slit lengthwise in the direction of its axis and thereby the portion of said tubular extension that is received in said aperture is expansible transversely of said axis and said securing means comprises means for expanding said slit portion against the walls of said round aperture.

3. A construction as claimed in claim 1, in which said tubular extension is made of yieldable material and said portion of said tubular extension that is received in said aperture is subdivided into at least two arcuate parts and said securing means comprises a threaded element in threaded connection with one of said arcuate parts and operating upon the other of said arcuate parts to effect spreading thereof in response to turning of said threaded element.

4. A construction as claimed in claim 1, in which said transformer structure has projecting from said fourth of said casing side faces a plurality of spaced tongue-like extensions whose ends are in projection spaced from the axis of said tubular extension by a distance substantially equal to x , said extensions being thereby adapted to engage the supporting surface against which said outlet box rests by its back wall and thereby prevent rotational displacement of said transformer structure relative to said wall.

5. A construction as claimed in claim 4, in which said tongue-like extensions have scored weakened sections adjacent their junction to said transformer structure whereby one or more may be broken off.

6. In construction of the character described, in combination, an outlet box having a round aperture in a wall thereof, a transformer structure having a core and windings and an enclosing casing therefor, said casing having means for securing it to said outlet box comprising a radially expansible tubular extension projecting from the casing, said extension extending through said round aperture of the outlet box with an end portion thereof within said outlet box, said end portion of said tubular extension having an externally convex flange of greater radial dimension than that of said outlet box aperture, said transformer structure having conductors extending from said windings outwardly through said tubular extension, said flange being internally concave and having seated therein an insulating disc which closes the end of said extension, said disc having aperture means therein for the passage therethrough of said conductors, whereby the latter are brought into said outlet box.

7. In construction of the character described, in combination, an outlet box having a round aperture in a wall thereof, a transformer structure comprising a core and windings and a casing therefor, said casing having a tubular extension communicating with the interior of said cas-

ing and having conductors extending therethrough to said windings, said tubular extension having a subdivided end portion receivable in said round aperture in the wall of said outlet box, and means for expanding said subdivided portion of said tubular extension against the inside periphery of said aperture.

8. A construction as claimed in claim 7, in which said casing comprises two dished-out half-housings respectively enveloping two sides of said core and windings and in which said expansible tubular extension comprises respectively a half-circular extension of one of said half-housings with its axis falling in the plane of the core face enveloped by said half-housing and a half-circular partially severed extension of the other half-housing displaced from the latter so that its axis is coincident with the axis of said first-mentioned half-circular extension, the partial severing of said second half-circular extension from its half-housing permitting it bodily to yield toward or away from the other half-circular extension, said expanding means comprising controllable means coacting between said two half-circular extensions for holding said bodily yieldable extension away from the other half-circular extension.

9. A transformer construction for mounting in the round aperture of a support such as an outlet box, comprising a core having two opposed parallel faces and winding means projecting beyond said faces and two dished-out half-housings enveloping the projecting winding means and the core at the respective parallel faces of the core, each of said half-housings having a half-circular extension which together form a tubular extension whereby the latter is receivable at its end into a round aperture of a support, one of said half-circular extensions having a connection with its half-housing that is bendable, and means for forcing said one half-circular extension in a direction away from the other by a pivoting movement with said bendable connection as an axis.

10. A construction as claimed in claim 9, in which each of said half-circular extensions terminates in flange-like means projecting radially therefrom and receivable through said round aperture in the support from one side of the latter and adapted, upon movement of said second half-circular extension away from the other, to engage against the other side of the support.

11. A construction as claimed in claim 9, in which said tubular extension has communication with the interior of the casing formed by said half-housings and has conductors extending therethrough from said winding means, each of said half-circular extensions having internal opposed seats, and an insulating disc in said tubular extension and seated in said opposed seats, said insulating disc having aperture means for the passage therethrough of said conductors.

12. A construction as claimed in claim 9, in which said forcing means comprises a bolt anchored at one point in one of said half-circular extensions and passing through a threaded hole in the other half-circular extension opposite said anchored point, whereby turning said bolt deforms said tubular extension by forcing one half-circular extension away from the other and thus changing the length of a diameter of said tubular extension.

13. A construction as claimed in claim 9, in which said tubular extension has communication with the interior of the casing formed by said

half-housings and has conductors extending therethrough to said winding means, and an apertured insulating disc substantially closing off said tubular extension and having said conductors passing therethrough, each of said half-circular extensions having axially spaced means of substantially 180 degrees extent for respectively receiving therebetween opposed peripheral portions of said insulating disc, each of substantially 180 degrees extent.

14. A transformer construction for mounting in the round aperture of a support such as an outlet box or the like comprising a core and coating winding means and a casing therefor, said casing having a tubular extension communicating with the interior of said casing and having conductors extending therethrough from said winding means, said tubular extension being subdivided into opposed arcuate end portions whereby the latter are receivable in the round aperture of a support and being substantially closed by an apertured insulating disc through which said conductors pass, said end portions having flange-like means directed inwardly for holding said insulating disc, and means for spreading apart opposed arcuate portions that are at opposite ends of a diameter without material spreading apart of arcuate portions thereof at opposite ends of a diameter that makes a right angle with said first-mentioned diameter and thereby maintain the holding action on said disc by said flange-like means.

15. In construction of the character described, in combination, a transformer core of the shell type having windings thereabout, a casing comprising two half-housings for enclosing said core and windings from opposite sides of said core, a thermally-responsive switch comprising an insulating support and two substantially parallel opposed conductive switch elements with means insulatingly securing one end of each at one point in and to said insulating support whereby the other ends thereof are free for relative circuit-controlling movement, said support having means securing it in fixed relation to said core and said half-housings having juxtaposed complementary half-circular extensions which together form a tubular extension for the passage of a conductor therethrough, and a conductor extending through said tubular extension and anchored to said insulating support at a point substantially coincident with the point at which said switch elements are secured thereto.

16. A transformer construction as claimed in claim 15, in which said insulating support comprises a plate-like member having a portion extending between said windings and a part of said core with its plane at right angles to the axis of said tubular extension, said switch elements being on opposite sides of said plate-like member and the securing means for said switch elements comprising a hollow clamping means having said conductor extending thereinto and secured thereto, said plate-like member having portions thereof in between said switch elements cut away whereby the free ends of said switch elements can move as a unit under straining of said plate-like member at said securing means.

17. In construction of the character described, in combination, a transformer core of the shell type having windings thereabout, a casing comprising two half-housings for enclosing said core and windings from opposite sides of said core, said half-housings having complementary half-circular extensions forming a tubular mounting

extension, and a relatively heavy conductor passing through said tubular extension and having its inner end bent into a hook, said core and windings having secured thereto a clamping lug that is bent over the short end of the hook with the axis of bending substantially parallel to the axis of said tubular mounting extension and to the line of said conductor.

18. In construction of the character described, in combination, a transformer core of the shell type having windings thereabout, a casing comprising two half-housings for enclosing said core and windings from opposite sides of said core, said half-housings having complementary half-circular extensions forming a tubular mounting extension, the axis of said tubular extension extending at right angles to the axis of said windings and the core portion therein, and two relatively heavy lead-in conductors extending axially through said tubular extension and transversely of the axis of said windings and terminating in hooks at the respective ends of said windings, said windings and said core portion having interposed therebetween a sheet-metal strap terminating at the respective ends of said windings in bendable lugs respectively bent over the short ends of said hooks with the axis of bending substantially parallel to the axis of said tubular mounting extension and to the line of the conductors therethrough.

19. A transformer construction comprising a transformer core having windings thereabout and enclosing casing means therefor, with means for clamping the latter and said core together, a thermally-responsive switch comprising an insulating plate-like support having an edge portion seated against said core and an opposed edge portion engaged by said casing means whereby said insulating support is clamped between the two, said insulating plate-like support having two relatively long substantially parallel opposed conductive switch elements in circuit with said windings and having means insulatingly secured one end of each to said insulating support at substantially the same point in the plate-like support and having the free ends thereof juxtaposed to each other for relative circuit controlling movement therebetween, whereby, should said plate-like support be strained and the portion thereof at which said switch element ends are secured be distorted out of normal relation to the rest of the support, said other ends of said long switch elements are shifted together substantially as a unit.

20. A transformer construction as claimed in claim 19 in which said parallel switch elements are on opposite sides of said plate-like support, the latter having portions thereof in between said switch elements cut away to provide clearance space for relative circuit controlling movement between said free ends of said switch elements and for movement thereof as a unit.

21. A transformer construction comprising a core and windings and having mounting means projecting therefrom comprising two substantially half-circular sheet material parts which together form a hollow annulus and means supporting said two half-circular parts in complementary juxtaposed relation to form a hollow annulus comprising means rigidly mounting one of them from said core and means supporting the other from said core and having hinge-like connection to said other part thereby to permit movement thereof toward or away from the other half-circular part to change the spacing therebetween

and to enlarge or shorten a diametrical dimension of said annulus, a conductor extending from said windings through said hollow annulus, and means coacting between said two parts for controlling the spacing therebetween, whereby said annulus with said conductor may be entered into a round aperture in a support and clamped against the peripheral walls thereof.

22. A transformer as claimed in claim 21 in which said last-mentioned means comprises a screw having threaded connection with one of said half-circular parts and engaging the other.

23. A transformer as claimed in claim 22 in which said screw extends substantially diametrically of said annulus and is by-passed by said conductor, said screw having thereabout an insulating sleeve.

24. A transformer constructed comprising sheet-metal casing means having therein a transformer core and windings with a conductor extending from the latter, said casing means having means for mechanically connecting it to a support, said means comprising an external sheet-metal annulus projecting from said casing means, said annulus having a peripheral flange at its outer end and both said flange and said end being subdivided into opposed relatively movable arcuate portions by slit means extending lengthwise of the axis of the annulus and toward the inner end thereof whereby the resultant arcuate portions thereof are relatively displaceable in a direction toward or away from the axis of said annulus to dimensionally lessen the outer end and said flange of said annulus for passage of the flange through a round aperture of a support and to dimensionally enlarge said flange after passage through a round aperture of the support, said conductor extending through said annulus and outwardly through the outer end thereof.

25. In construction of the character described, in combination, an outlet box having a back wall to rest against a supporting surface and side walls and having a round aperture in a side wall thereof spaced from the center of the aperture to the plane of the back wall of the outlet box by a distance x , a transformer structure having a core and coacting windings and an enclosing casing therefor presenting four side faces, said casing having mounting means receivable in said round aperture, said mounting means having an axis which is parallel to said four side faces of the transformer structure and is displaced from three of said side faces by a distance greater than x and from the fourth side face by a distance less than x by an amount providing a factor of safety against fire hazard whereby said axis and the axis of said round hole in the outlet box can be brought into coincidence only when said fourth side face is toward the plane of said supporting surface, said mounting means having end portions that terminate at points on a circle that is of a diameter commensurate with the diameter of said round aperture and are thereby received in the latter when said fourth side face of the transformer structure faces toward the plane of said supporting surface, and means for securing said mounting means to said outlet box side wall with the said end portions thereof received in said

round aperture and with said two axes substantially coincident.

26. In construction of the character described, in combination, an outlet box having a round aperture in a wall thereof, a transformer structure comprising a core and windings and a casing therefor, said casing having a tubular extension communicating with the interior of said casing and having conductors extending therethrough to said windings, said tubular extension having a sub-divided end portion presenting two relatively movable clamping parts spaced substantially on a diameter commensurate with the diameter of said round aperture and receivable in said round aperture in the wall of said outlet box for substantially juxtaposing said two clamping parts within said round aperture to substantially diametrically opposite peripheral points of the latter, and means for moving one of said two clamping parts relative to the other in a substantially diametrical direction away from the other and thereby expanding the diametric spacing of said two clamping parts of said sub-divided portion of said tubular extension to clamp them against the inside periphery of said aperture.

27. In construction of the character described, in combination, an outlet box having a round aperture in a wall thereof, a transformer structure comprising a core and windings and a casing therefor, said casing having a tubular extension communicating with the interior of said casing and having conductors extending therethrough to said windings, said tubular extension having a sub-divided end portion comprising two relatively movable clamping parts spaced substantially on a diameter commensurate with the diameter of said round aperture, said extension having secured thereto adjacent said clamping parts a transverse apertured insulating plate through which said conductors extend for passage through said aperture and into said box, said two clamping parts being receivable in said round aperture in the wall of said outlet box substantially in juxtaposition to substantially diametrically opposite peripheral points of the aperture and with said transverse insulating plate positioned substantially at said aperture for insulating passage of said conductors into the outlet box, and means for moving one of said two clamping parts relative to the other in a substantially diametrical direction away from the other and thereby expanding the diametric spacing of said two clamping parts of said sub-divided portion of said tubular extension to clamp them against the inside periphery of said aperture and for thereby fixing the position of said insulating plate relative to said aperture.

LEO L. VERKUIL.
